Primary Examiner — Sheryl Lane*Assistant Examiner* — Calvin E Vansant*(74) Attorney, Agent, or Firm* — Cantor Colburn LLP(57) **CLAIM**

The ornamental design for an adapter for mounting optical equipment to mobile computer, as shown and described.

DESCRIPTION

FIG. 1 is a perspective view of an adapter for mounting optical equipment to mobile computer.

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a right side elevational view; and,

FIG. 7 is a Cross sectional view of FIG. 6 along line 7-7.

The broken lines depict environmental subject matter only and form no part of the claim.

1 Claim, 7 Drawing Sheets(56)
